UNITED STATES PATENT OFFICE.

CHARLES E. JONES, SR., OF FLORENCE, ALABAMA, ASSIGNOR OF TWO-THIRDS TO W. J. FLANAGIN AND ROMULUS J. HOFFMAN, BOTH OF SAME PLACE..

LOCK.

SPECIFICATION forming part of Letters Patent No. 453,192, dated June 2, 1891.

Application filed January 14, 1891. Serial No 377,704. (Model.)

To all whom it may concern:

Be it known that I, CHARLES E. JONES, Sr., a citizen of the United States, residing at Florence, in the county of Lauderdale and State of Alabama, have invented certain new and useful Improvements in Locks; and I do hereby declare the following to be a full, clear, and exact description of the invention, such as will enable others skilled in the art to which it appertains to make and use the same.

The special object of the invention is to make a lock adapted to be conveniently used on the doors of tills, drawers, cupboards, closets, or wardrobes, the locking and unlocking being done by the knob-spindle, which may also be used as a drawer-pull, while the locking may be done without the key, so as not to be preceptible to a looker on.

Figure 1 of the drawings is an elevation showing the inside of the lock; Fig. 2, a detail view of spindle with its attachments; Fig. 3, a similar view of the key and cylinder apart; Fig. 4, a similar view of the fence-plate; Fig. 5, a similar view of the locking-bolt, and Fig. 6 is a plan view of that part or plate of lock-case through which the cylinder is entered.

In the drawings, A represents the lock-case, made in two parts a a' , separately connected by two screws a^2 a^3 , which work through part a into raised nuts a^3 a^3 on the part a' . In a hole a^4 and upper groove a^5 is loosely secured a cylinder B, which has the slot b , and is made of greater diameter at b' than at b^2 . Through the upper groove a^5 of case and the slot b of cylinder when registering with each other is entered the key C, having the side studs c c' c^2 of differing heights for raising the tumblers D, which have end-open slots d , correspondingly different in height. By this relative construction all the tumblers may be raised at once to make all the slots register with each other and at the same time be in line with the fence e , which is arranged on a sliding plate E. The tumblers D are all pivoted on the same stud F and held down out of a horizontal position by a spring f , which bears on the vertical pin f' of the case. Next to these tumblers I arrange the plate E, containing the fence e on one side and the stud e' on the

other. This stud moves in a slot g of the lock-bolt G when the fence-plate is caused to slide, while the plate E has a slot e^2 to guide it as it slides on the case-stud F. The bolt G is held forward by a spring g' , and its shank G' is supported by a case-flange g^2 . The plate E has a tooth e^3 , in which works a pawl e^4 , pivoted to case and pressed down by a spring e^5 , which rests with its rear end against the pin e^6 of the case. This pawl e^4 serves to hold the plate fast when it has been retracted, and thus to allow the bolt also to be retracted. In this position the fence e rests in the slots of all the tumblers.

H is a cylinder, having a square hole to receive the squared part k of the spindle K, which spindle has the knob k' , shoulder k^2 , against which is supported the face-plate k^3 , and the slotted sliding sleeve k^4 . This sleeve is held at different points on the squared portion of the spindle to suit different thicknesses of door.

On the cylinder H is a lug h , which goes under the plate E and raises the pawl e^4 whenever the spindle K is turned to the right, and when the spindle is then turned farther another stud h' presses a shoulder e^7 of the plate E, so as to move it forward and carry the fence e out of the tumbler-slots, when the bolt is thrown forward by its spring. The fence-plate is now pressed in front against the shoulder m of the bolt G and locked in that position by the tumblers which have been thrown down in front by their rear spring. To retract the bolt it is necessary to raise the tumblers with the key and throw back the fence-plate E with the spindle-stud h' . Then the spindle-stud h will press the shoulder g of the bolt and retract it. When the plate E is run back, the pawl e^4 springs behind the tooth thereof and locks it back. The key C not only raises the tumblers by the studs c c' c^2 , but immediately afterward slides back the plate E by means of a projection c^3 , which fits a corresponding recess e^8 in the slide. Thus it will be perceived that the plate E may be slid back either by the key or the knob-spindle; but the tumblers can only be lifted by the key, while the plate E can only be unlocked

from the pawl by the spindle. Hence the door cannot be locked without using the spindle or unlocked without using the key.

What I claim as new is—

- 5 The spring-pawl e^4 , pivoted to case, and the knob-spindle cylinder H, having the lugs $h\ h'$, in combination with the slide-plate E, having the fence e , stud e' , slot e^2 , through which passes the case-stud F, the tooth e^3 , in which

works the pawl e^4 , pivoted on the case, and the spring-bolt G, having the slot g , as and for the purpose set forth.

In testimony whereof I affix my signature in presence of two witnesses.
